UNITED STATES PATENT OFFICE

2,550,440

TAKE-UP DEVICE

William H. Atkisson, Monrovia, Calif.

Application December 12, 1947, Serial No. 791,410

2 Claims. (Cl. 254—78)

1

This invention has to do generally with work take-up or clamping devices, and is directed particularly to improvements in clamp-like devices usable to take up or tighten a flexible member about the work or load, and to securely retain the member in successive tightened conditions.

My major object is to provide a novel and effective device whereby a work-surrounding member may be tightened through successive intervals or stages, and retained in its tightened condition between such intervals, all in a manner avoiding interference with each tightening manipulation.

Structurally the invention contemplates a take-up assembly comprising a pair of sections relatively movable to tension or shorten the aforesaid member about the work, and an associated holding element engageable with the member to retain its tightened condition between successive operations.

The take-up action may be accomplished using a structure of the general type disclosed in my copending application Serial No. 617,041, filed September 18, 1945, on Clamp and Take-Up, now abandoned, employing a pair of pivoted sections one having a lever handle and the other carrying a part engageable with the flexible member to tension the latter as the sections are moved by operation of the lever handle. In accordance with the present invention, a holding element is pivotally associated with the take-up parts, so as to be movable into and out of retaining engagement with the flexible member between successive operations of the tensioning parts.

The invention contemplates various additional objects and details having to do with such features as the interfitting and pivotal relation of the parts, and particularly their adaptability for connection with a chain form of flexible member. All these will be understood to better advantage from the following description of an illustrative embodiment shown by the accompanying drawing, in which:

Fig. 1 is a view showing the take-up device in side elevation;

Figs. 2 and 3 are fragmentary enlarged elevations showing the positions of the parts in successive stages of the take-up action; and

Fig. 4 is a plan section taken on line 4—4 of Fig. 3.

Referring first to Figs. 1 and 4, the device is shown to comprise what may be termed a body section 10, the forward extent of which is bifurcated to form the transversely spaced arms 11.

2

At its opposite end, the body carries an appropriate means for attachment to a flexible work-encircling member; for example, a hook 12 engageable with one end of a chain 13 which, as will be understood, may be placed about a load to be retained, as on a truck, by application and tensioning of the encircling chain. The device has a handle section 14, the forward bifurcated end offset portion 15 of which is received within the bifurcated end 11 of the body and pivotally attached thereto at 16. By virtue of their offset and interfitting, bifurcated end relation, the body and handle sections are movable into the substantially parallel positions shown in Fig. 1.

A hook arm 17 received within a pivot connected at 18 to the bifurcated end portion 15 of the handle section, projects forwardly to be encircled, within one of the chain links. As will be apparent, by swinging the handle section upwardly to the position of Fig. 2 and then engaging the hook arm 17 with the chain, the latter may be tightened about the load upon bringing the handle section down and returning the parts to the positions of Fig. 1, as a result of which the hook and chain end are moved longitudinally of the device a distance corresponding to the axial throw of the pivot connection 18.

The invention is more particularly concerned with the retention of the chain in its successive tightening manipulations of the handle section and hook 17 as described. Such retention of the chain is effected by a U-shaped holding element 19, the arms 20 of which are pivotally connected to the body section 10, as by accommodating the turned ends 21 of the arms within openings 22 in bracket plates 23 carried by the body section arms 11. The holding element 19 has at its free end a claw 24 engageable with the links of the chain 13 to hold the chain tension. The holding element is accommodated to the action of the hook 17, as later described, in its pulling action on the chain, by providing arms 20 with hinges at 25, so that the element in effect becomes longitudinally flexible.

In connection with the operation of the device, assume the handle section 14 to be swung forwardly and hook 17 engaged with the chain as shown in Fig. 2. The holding element 19 may assume the illustrated position from application to the chain in retaining a previously tightened condition. As the handle section is swung toward the body, the hook 17 rises, as illustrated by the intermediate progression of Fig. 3, while moving rearwardly to tighten the chain. The resultant shortening of the distance between the claw

24 and the pivot locations 21 causes the holding element to buckle at the hinges 25 progressively as the hook 17 is carried throughout its range of tightening movement. Thereafter, with the body and handle sections restored to the position of Fig. 1, the holding element 19 may be distended and the claw 24 engaged with the chain to retain its tightened condition either permanently, or while the hook 17 is being re-engaged with the chain for a successive tightening operation.

I claim:

1. A take-up device of the character described, comprising a body section adapted to extend alongside a work unit and attachable to one end of a chain extending about the work, said body having a first side adapted to face the work, a handle section connected to the body for swinging movement at a second side thereof opposite said first side, a hook pivotally connected to the handle section and engageable with an opposite end of the chain, said hook being movable longitudinally of the body to tighten said chain about the work by swinging the handle along said second side of the body, and a holding claw pivotally attached to the body and engageable with successive lengths of the chain to hold the chain in tightened condition about the work between successive tightening operations of said hook, said claw having a hinge joint intermediate its ends at which the claw flexes during a tightening operation, said hinge joint of the claw being received in a first normal position in the extended condition of the claw, said hinge joint being movable upon flexure of the claw during a tightening operation outwardly away from the work and beyond the chain to a location at the side of said normal position and the chain corresponding to said second side of the body, said hook and the handle section being positioned during a tightening operation out of the path which the hinge joint and other portions of the claw, while the

claw is connected to the chain, follow in moving away from the work and outwardly beyond the chain.

2. A take-up device of the character described, comprising a body section adapted to extend alongside a work unit and attachable to one end of a chain extending about the work, said body having a first side adapted to face the work, a handle section connected to the body for swinging movement at a second side thereof opposite said first side, a hook pivotally connected to the handle section and engageable with an opposite end of the chain, said hook being movable longitudinally of the body to tighten said chain about the work by swinging the handle along said second side of the body, and a holding claw pivotally attached to the body and engageable with successive lengths of the chain to hold the chain in tightened condition about the work between successive tightening operations of said hook, said claw including two parallel arms each having a hinge joint intermediate its ends at which the claw flexes outwardly away from the work during a tightening operation, said two arms of the claw being laterally offset to the opposite sides of said hook and the handle section to thereby permit movement of the hinge joints outwardly away from the work during a tightening operation.
